FUNGICIDAL COMPOSITIONS

William E. Burt, Baton Rouge, La., assignor to Ethyl Corporation, New York, N.Y., a corporation of Virginia
No Drawing. Filed Feb. 28, 1964, Ser. No. 348,258
19 Claims. (Cl. 167—58)

This invention relates to novel fungicidal compositions and their use in the treatment of fungal infections.

In my copending application Serial No. 161,367, filed December 22, 1961, now U.S. 3,123,523, of which this application is a continuation-in-part, I described the use of arene Group VIB metal tricarbonyls in the treatment of fungi which are pathogenic to animals, vegetables, and man. A preferred embodiment of the invention described in said earlier application comprises the treatment of fungi with a compound having the formula:

wherein M is a metal of Group VIB of the Periodic Table, X is a halogen; a is an integer having the value 0 to 1; Y is selected from the class comprising

wherein R_1 and R_2 are alike or different and selected from the class consisting of hydrogen and alkyl groups having one to about 4 carbon atoms; b is an integer having the value 0 to 1; R is selected from the class consisting of hydrogen and alkyl groups having one to about 4 carbon atoms; and c is an integer having the value 0 to 3, such that when $c=3$, $a=0$ and $b=0$. Compounds of this type can be prepared by the general method of Nicholls et al., Proc. Chem. Soc. (1958), page 152.

When the subscripts a , b , and c , in the above formula are equal to zero, the compound is benzene chromium tricarbonyl. When the subscript a is equal to one, and b and c are both equal to zero, the compounds are the halo-benzene tricarbonyls of the metals of Group VIB. Benzene chromium tricarbonyl and chlorobenzene chromium tricarbonyl are highly preferred compounds since the aromatic portion of the molecule is available at low cost.

When a and b are equal to zero and c has a value from one to three, the compounds are hydrocarbon substituted benzene metal tricarbonyls. This class of compounds is represented by the chromium tricarbonyls of toluene, o-diethylbenzene, o, m, p-xylanes, p-isobutyltoluene, mesitylene, and the like. The preferred compounds of this class are the compounds having methyl substituents on the benzene ring. The most preferred compounds are toluene chromium tricarbonyl, the xylene chromium tricarbonyls, and mesitylene chromium tricarbonyl.

When a and c are equal to zero and b is equal to one, the compounds are the chromium tricarbonyls of aniline, N,N-dimethylaniline, acetanilide, acetophenone, benzyl alcohol, methylbenzoate, and the like. The preferred compounds of this class are acetophenone chromium tricarbonyl, methylbenzoate chromium tricarbonyl, aniline chromium tricarbonyl, and N,N-dimethylaniline chromium tricarbonyl.

When more than one of the subscripts in the above formula is equal to one, compounds such as the chromium tricarbonyls of o-toluidine, p-methylanisole, m-chloroaniline, and the like are described. The o-toluidine and

2

p-methylanisole compounds are preferred because of their commercial availability.

This invention is directed to the provision of novel fungicidal compositions (which contain, as a principal active ingredient, a fungitoxic amount of one or more of the arene Group VIB metal tricarbonyls, described and formulated above) that are especially efficacious in the treatment of external fungal infection of human beings. The provision of compositions of this type is a primary object of this invention. Another object is to provide solid, semi-solid, or liquid preparations (containing fungitoxic amounts of one or more arene Group VIB metal tricarbonyls) which can be applied to human epidermis.

The objects of this invention are satisfied by providing solid, semi-solid, or liquid preparations containing a fungitoxic amount of one or more arene Group VIB metal tricarbonyls in a lotion, ointment, salve, or cream base.

The fungicidal compositions of this invention have many inherent advantages. For example, not only do they contain a highly potent arene metal carbonyl, but they are readily prepared by methods well known to those skilled in the art of the preparation of lotions, ointments, salves, or creams. Furthermore, they are readily dispensed and applied to the locus of the fungi. Still another advantage of the compositions of this invention is that they provide a protective area over the infected part when applied to the locus of the fungi. Many of the preparations of this invention contain a high concentration of an insoluble oleaginous substance. Formulations of this type are not readily removed from the infected area by the rubbing of clothing or exposure to water. Hence, they provide a more permanent application than preparations such as dusts and solutions. Another advantage of the compositions of this invention is that the oleaginous substances, alcohols, and esters employed in their preparation have emollient properties which improve the texture of epidermis when applied thereto. Many of the compositions of this invention, especially those which contain an emulsion-type base, are not very visible when applied to an exposed area of the skin. Hence, they are highly acceptable from a cosmetic viewpoint. Furthermore, the formulations of this invention are more stable than many other fungicidal compositions containing arene Group VIB metal tricarbonyls. Thus, they have a longer shelf life and, therefore, are commercially attractive.

As stated above, many of the compositions of this invention contain a base comprising an oleaginous substance. The exact nature of the oleaginous substance is not critical, provided that the substance is non-toxic and non-drying. By non-drying, I mean those oleaginous substances which tend to become more solid upon exposure to air. Hence, I preferably exclude high quantities of drying oils such as linseed oil and the like from my preparations. However, minor amounts of these drying oils, say up to about 3%, can be employed if desired.

In general, the oleaginous substance may be any non-toxic, non-drying, inert water-insoluble material such as the natural or synthetic oils, fat, and waxes. As appreciated in the art, waxes commonly are esters of long-chain fatty acids with long-chain fatty alcohols. Usually the alcohols are monohydric; that is, they contain only one hydroxy function per molecule. In general, the oils and fats are esters of long-chain fatty acids with glycerol. The oils are liquids at room temperature while the fats are not. Other substances which can be employed include higher paraffinic substances. Usually mixtures of these, such as mineral oil, paraffin wax, or petrolatum are employed. Polymers of alcohols such as polyethyleneglycols having a molecular weight within the range of

about 1500 to about 4000 (Carbowaxes), and similar substances can also be employed if desired.

Common waxes which can be employed are beeswax or purified beeswax. Cetyl palmitate and spermaceti can also be employed. Fats and oils which may be employed include cocoa butter, peanut oil, rapeseed oil, coconut oil, olive oil, cod liver oil, whale oil, fish oil, and the like.

One preferred embodiment of this invention is a composition which contains a fungitoxic amount of an arene Group VIB metal tricarbonyl in a substantially non-aqueous lotion, salve, cream, or ointment base. These preparations comprise from about 30 parts per million to about 30% by weight of at least one arene Group VIB metal tricarbonyl in an oleaginous base which does not contain more than about 1% by weight of water. Preferred formulations of this type contain less than about 0.5% water. Hence, this embodiment of this invention comprises:

(1) As a principal active ingredient, a fungitoxic amount of a compound having Formula I, and

(2) As a carrier therefor, a substantially anhydrous, non-toxic, non-drying, inert oleaginous substance.

A preferred type of this class of compositions also contains, per each 100 parts by weight of oleaginous substance, from about 5 to about 70 parts of a compatible higher alcohol having from about 13 to about 30 carbon atoms. Alcohols of this type are illustrated by cetyl alcohol, stearyl alcohol, octadecyl alcohol, cholesterol, a mixture of the alcohols derived from lanolin by hydrolysis (lanolin alcohols), and the like. The alcohols increase the emollient qualities of the formulations.

Another preferred type of fungicidal composition contains, per each 100 parts of oleaginous substance, from about 10 to about 50 parts of an insoluble, inert opaque solid. Solids used in this embodiment may be organic in nature such as stearic acid, starch, and the like, or inorganic, such as gypsum, mica, talc, apatite, bentonite, and the like. These substances thicken the preparation.

A highly preferred non-aqueous fungicidal composition of this invention comprises a fungitoxic amount of at least one arene Group VIB metal tricarbonyl and, as a carrier therefor, an oleaginous substance of the type

groups containing from 3 to 8 carbon atoms and are further characterized by being branched on their alpha carbon atoms; such that the concentration of the arene Group VIB metal tricarbonyl is from about 30 parts per million to about 30% by weight, and the concentration of said hindered phenol is from about 0.001 to about 5%, and preferably from about 0.25 to about 3 percent, by weight. The hindered phenols stabilize the preparations from oxidative deterioration.

Typical phenols of Formula II include 4,4'-methylenebis(2,6-diisopropylphenol); 4,4'-methylenebis(2,6-di-sec-butylphenol); 4,4'-methylenebis(2-isopropyl-6-tert-butylphenol); 4,4'-methylenebis[2,6-di-(2-octyl)-phenol]; 4,4'-methylenebis[2-sec-butyl-6-(2-hexyl)-phenol]; 4,4'-methylenebis[2-isopropyl-6-(1,1,3,3-tetramethylbutyl)phenol], and the like.

The preferred class of compounds of this type includes 4,4'-methylenebis(2-tert-butyl-6-tert-amylphenol); 4,4'-methylenebis(2,6-di-tert-amylphenol); 4,4'-methylenebis[2,6-di-(1,1,3,3-tetramethylbutyl)phenol]; 4,4'-methylenebis[2-tert-butyl-6-(1,1,2,2-tetramethylpropyl)-phenol], and the like.

Formulations of the type described above are prepared by incorporating the desired amount of arene Group VIB metal tricarbonyl in the quantity desired in the desired base. Typical bases of this type are described below.

BASE 1

A mixture having the following ingredients is prepared. All parts are by weight.

	Parts
Cholesterol	10
Stearyl alcohol	30
White wax	80
35 Wool fat (anhydrous)	150
White petrolatum	730

The ingredients are melted together on a water bath and mixed thoroughly. Thereafter, the mixture is removed from the bath and stirred until it congeals. Table I below further illustrates bases of this type. The numbers in the columns are parts by weight.

TABLE I

Ingredient	Bases											
	2	3	4	5	6	7	8	9	10	11	12	
Lanolin (anhydrous)	5	5	15.6		10.4					5.5	7.5	16.8
Petrolatum (white)	15			26.1								
Petrolatum (white)	50	90	76.0	10.9	89.6	100				83.5		83.2
Mineral Oil U.S.P.	30			62.13			100					
White beeswax		5	8.3							40.5		
Carbowax 4000										59.5		
Carbowax 400												
Hydrogenated cottonseed oil												92.6
Cetyl alcohol	5		31.2		4.16							
Stearyl alcohol			10.4									
Cholesterol							8.9					
Lanolin alcohols					66		2.2					
Glyceryl monostearate										13.8		
Stearic acid										2.2		
Magnesium oleate								33.3				
1,2,6-hexanetriol									19			

described above and, per each 100 parts by weight of said oleaginous substance, from about 5 to about 70 parts of a higher alcohol as described above, from about 10 to about 50 parts of an inert opaque solid as described above, and a hindered phenol having the formula:

wherein the groups designated by R_1 and R_2 are alkyl

65 This base is prepared by thoroughly blending 10 parts of starch U.S.P to the ingredients of Base 3 in Table 1.

BASE 14

This base is prepared by adding and thoroughly mixing 50 parts of starch to the ingredients of Base 3.

BASE 15

This base is prepared by adding 50 parts of bentonite to the ingredients of Base 7 and thoroughly mixing the resultant mixture.

5
BASE 16

4,4'-methylenebis(2,6-di-tert-butylphenol), 0.25 part, is thoroughly mixed with 100 parts of Base 7. A similar base is prepared by adding 2.0 parts of the phenol to 100 parts of Base 10.

The following example illustrates the substantially anhydrous oleaginous compositions of this invention. All parts are by weight unless otherwise noted.

Example I

Methylbenzoate chromium tricarbonyl, 30 parts, is thoroughly mixed with 999,970 parts of Base 1. The resultant fungicidal composition has a concentration of arene chromium tricarbonyl equal to 30 parts per million.

In a similar manner, using the same base, fungicidal compositions containing 50, 100, 300, 500, and 700 parts per million of methylbenzoate chromium tricarbonyl are prepared.

More concentrated foams containing 0.1, 0.5, 1, 3, 5, 7, 10, 15, 20, and 30 percent of arene chromium tricarbonyl are prepared by adding the requisite quantity of methylbenzoate chromium tricarbonyl to Base 1.

Example II

o-Xylene chromium tricarbonyl, 30 parts, is added to 999,970 parts of Base 5 to yield a fungicidal composition having 30 parts per million of arene chromium tricarbonyl.

In a similar manner, using the same base, fungicidal compositions containing 50, 100, 300, 500 and 700 parts per million of *o*-xylene chromium tricarbonyl are prepared. More concentrated foams containing 0.1, 0.5, 1, 3, 5, 7, 10, 15, 20, and 30 percent of arene chromium tricarbonyl are prepared by adding the requisite quantity of *o*-xylene chromium tricarbonyl to Base 5.

Example III

p-Xylene chromium tricarbonyl, 30 parts, is added to 999,970 parts of Base 3 to yield a fungicidal composition having 30 parts per million of arene chromium tricarbonyl.

In a similar manner, using the same base, fungicidal compositions containing 50, 100, 300, 500 and 700 parts per million of *p*-xylene chromium tricarbonyl are prepared. More concentrated foams containing 0.1, 0.5, 1, 3, 5, 7, 10, 15, 20, and 30 percent of arene chromium tricarbonyl are prepared by adding the requisite quantity of *p*-xylene chromium tricarbonyl to Base 3.

Example IV

o-Toluidine chromium tricarbonyl, 30 parts, is added to 999,970 parts of Base 6 to yield a fungicidal composition having 30 parts per million of arene chromium tricarbonyl.

In a similar manner, using the same base, fungicidal compositions containing 50, 100, 300, 500 and 700 parts per million of *o*-toluidine chromium tricarbonyl are prepared. More concentrated foams containing 0.1, 0.5, 1, 3, 5, 7, 10, 15, 20 and 30 percent of arene chromium tricarbonyl are prepared by adding the requisite quantity of *o*-toluidine chromium tricarbonyl to Base 6.

Example V

Fungicidal compositions containing 0.1% of arene chromium tricarbonyl are prepared by adding one-part-portions of toluene chromium tricarbonyl to 999-part portions of Bases 2, 4, 7, 8, 9, 10, 11 and 12. Similar preparations are prepared by adding similar quantities of anisole chromium tricarbonyl and acetophenone chromium tricarbonyl to similar quantities of the same bases. Similar formulations containing benzene chromium tricarbonyl, aniline chromium tricarbonyl, toluene chromium tricarbonyl, and aniline chromium tricarbonyl are also prepared.

6

Example VI

Fungicidal compositions containing 0.5% of chlorobenzene chromium tricarbonyl are prepared by adding five-part-portions of chlorobenzene chromium tricarbonyl to 995-part-portions of Bases 13, 14, 15 and 16.

Similarly, one-part-portions of benzene chromium tricarbonyl are added to 999-part-portions of Bases 13, 14, 15 and 16 to yield fungicidal compositions which contain 1% of benzene chromium tricarbonyl.

Five hundred-part-portions of *o*-toluidine chromium tricarbonyl are added to 999,500-part-portions of Bases 13-16 to yield fungicidal compositions which contain 500-parts per million of the *o*-toluidine chromium tricarbonyl.

Example VII

Methylbenzoate chromium tricarbonyl, 100 parts, is added to 999,900 parts of Base 2 to yield a fungicidal composition which contains 100 parts per million of methylbenzoate chromium tricarbonyl.

Similar compositions are prepared by adding 100-part-portions to 999,900-part-portions of Bases 2-16.

Other bases which are comparable to those defined and illustrated above which may be employed in this invention are White Ointment U.S.P and Yellow Ointment U.S.P.

The fungicidal compositions defined and illustrated above do not require a surface active agent. However, minor amounts (from about 1 to about 5 parts by weight per each 100 parts of oleaginous substance) of surface active agents can be employed if desired.

Solid, semi-solid, or thick, liquid emulsions comprise a second preferred type of fungicidal composition provided by this invention. The emulsions may be either an oil-in-water or water-in-oil type. Besides a fungitoxic amount of at least one arene chromium tricarbonyl, these compositions contain an oleaginous substance of the type described above and, for each 100 parts thereof, from about 90 to about 7500 parts of water. Preferably, these compositions contain from about 95 to 300 parts of water and most preferably, from about 100 to about 150 parts. Usually, distilled water is employed in these formulations. However, scented water such as rose water and the like can be employed if desired.

If desired, these compositions may contain other ingredients besides the oleaginous substance, water, and fungicidal agents. A preferred type of composition is an alcohol-water-oil emulsion which contains a higher alcohol of the type described above. Preferred alcohols are cetyl and stearyl alcohol. Usually from about 1 to about 1500 parts of alcohol of this type is employed for each 100 parts of oleaginous material. Preferred compositions contain from about 5 to about 100 parts of alcohol, and most preferably, from about 8 to about 30 parts.

If desired, the alcohol-water-oil emulsions may contain a surface active agent. The exact nature of the surface active agent is not critical, provided that it is compatible with the other ingredients in the composition.

Anionic surface active agents such as the alkali metal salts of long-chain organic sulfates, sulfonates, and the like are preferred. Highly preferred surface active agents are illustrated by sodium chlorocetane sulfate, sodium-N-oleyl N-methyl taurine, sodium cetyl sulfonate, sodium lauryl sulfate, and the like.

A surface active quantity of the surfactant is employed. Usually from about 2 to about 200 parts of surface active agent is used per each 100 parts of oleaginous substance. Preferably, from 2 to about 8 parts are employed.

If desired, the alcohol-water-oil bases illustrated above may contain minor amounts of an ester. Preferably, the esters are derived from acids having from about 12 to about 20 carbon atoms and from alcohols having from about 3 to about 10 carbon atoms. Highly

preferred esters of this type are illustrated by butyl stearate, diglycol distearate, trihydroxyethylamine stearate, diglycol dilaurate, diglycol dioleate, propylene-glycol-300 monostearate, and the like. The latter compound is a stearic acid ester of a propyleneglycol polymer having a molecular weight of about 300. Usually from about 5 to about 15 parts of an ester per each 100 parts of oleaginous substance is employed. Preferably from 6 to 13 parts are used, and most preferably from about 8 to about 11 parts.

Minor amounts of other ingredients can be employed in the alcohol-oil-water emulsion bases illustrated below. A preferred ingredient is a polyhydric alcohol having from about 2 to about 4 carbon atoms. Preferred alcohols of this type are propyleneglycol and glycerol. Preservatives such as benzoate of soda, metal-p-hydroxy benzoate, propyl-p-hydroxy benzoate, and the like can be employed if desired.

As with the anhydrous compositions described above, the alcohol-water-oleaginous substance emulsions employed in this invention preferably contain an inert, opaque solid and/or a hindered phenol. Phenols and inert opaque solids of the type described above are employed in this embodiment. In general, the same concentration of these substances is used although greater or lesser amounts can be employed if desired. Thus, a preferred embodiment of this invention comprises a fungitoxic composition comprising

(1) As a principal active ingredient, a fungitoxic amount of an arene Group VIB metal tricarbonyl having the formula

(I)

wherein R_1 and R_2 are alike or different and selected from the class consisting of hydrogen and alkyl groups having one to about four carbon atoms; b is an integer having the value 0 to one; R is selected from the class consisting of hydrogen and alkyl groups having one to about 4 carbon atoms, and c is an integer having the value 0 to 3, such that when $c=3$, $a=0$ and $b=0$, and

(2) As a carrier therefor, an emulsion base comprising an oleaginous substance and, per each 100 parts of said oleaginous substance, from about 1 to about 30 parts of a higher alcohol having from about 13 to about 30 carbon atoms; from about 95 to about 310 parts of water, and from about 2 to about 6 parts of an anionic surface active agent.

15 Highly preferred compounds of this type are further characterized in that they contain from about 10 to about 50 parts of an inert opaque solid. Other highly preferred compositions are further characterized in that they contain from about 0.001 to about 2% of a hindered phenol.

20 Bases containing a long-chain alcohol, water, and an oleaginous substance from which the fungicidal compositions of this embodiment are derived, are illustrated below.

BASE 17

Cetyl alcohol, 1500 parts, and 100 parts of beeswax are melted together. Thereafter, 1000 parts of propyleneglycol is added and the resultant mixture heated to about 65° C. In another vessel, 200 parts of sodium laurylsulfate are dissolved in 7200 parts of water heated to 65° C.

The oil phase (at 65° C.) is then added to the water phase slowly and with constant gentle stirring. Stirring is continued until an ointment-like consistency results.

35 Other alcohol-water oleaginous substance bases are illustrated in Table 2 wherein the numbers in the columns are by weight.

BASE 32

70 A base is prepared by adding 50 parts of bentonite to 100 parts of Base 22 and thoroughly mixing.

BASE 33

A base is prepared by adding 25 parts of fuller's earth to 100 parts of Base 23 and thoroughly mixing.

BASE 34

To 1000 parts of Base 21 is added and thoroughly blended 5 parts of 4,4'-methylenebis(2,6-di-tert-butylphenol). A similar base is prepared by adding identical parts of the phenol and Base 31 and thoroughly mixing.

BASE 35

One thousand parts of Base 18 is added and thoroughly blended with 2 parts of 4,4'-methylenebis(2,6-diisopropylphenol).

Example VIII

Methylbenzoate chromium tricarbonyl, 100 parts, is added to 999,900 parts of Base 18 and thoroughly mixed therewith. The resultant fungicidal composition contains 100 parts per million of methylbenzoate chromium tricarbonyl. In a similar manner, fungicidal compositions containing 50, 100, 300, 500, and 700 parts per million of methylbenzoate chromium tricarbonyl are prepared by thoroughly blending the requisite amount of the carbonyl with Base 18.

Similarly, fungicidal compositions containing 0.1, 0.5, 1, 3, 5, 7, 10, 15, 20, and 30 percent of methylbenzoate chromium tricarbonyl are prepared by adding the requisite portions of the carbonyl to the required portion of Base 18.

Example IX

o-Xylene chromium tricarbonyl, 100 parts, is added to 999,900 parts of Base 19 and thoroughly mixed therewith. The resultant fungicidal composition contains 100 parts per million of *o*-xylene chromium tricarbonyl. In a similar manner, fungicidal compositions containing 50, 100, 300, 500, and 700 parts per million of *o*-xylene chromium tricarbonyl are prepared by thoroughly blending the requisite amount of the carbonyl with Base 19.

Similarly, fungicidal compositions containing 0.1, 0.5, 1, 3, 5, 7, 10, 15, 20, and 30 percent of *o*-xylene chromium tricarbonyl are prepared by adding the requisite portions of the carbonyl to the required portion of Base 19.

Example X

p-Xylene chromium tricarbonyl, 100 parts, is added to 999,900 parts of Base 20 and thoroughly mixed therewith. The resultant fungicidal composition contains 100 parts per million of *p*-xylene chromium tricarbonyl. In a similar manner, fungicidal compositions containing 50, 100, 300, 500, and 700 parts per million of *p*-xylene chromium tricarbonyl are prepared by thoroughly blending the requisite amount of the carbonyl with Base 20.

Similarly, fungicidal compositions containing 0.1, 0.5, 1, 3, 5, 7, 10, 15, 20, and 30 percent of *p*-xylene chromium tricarbonyl are prepared by adding the requisite portions of the carbonyl to the required portion of Base 20.

Example XI

o-Toluidine chromium tricarbonyl, 100 parts, is added to 999,900 parts of Base 21 and thoroughly mixed therewith. The resultant fungicidal composition contains 100 parts per million of *o*-toluidine chromium tricarbonyl. In a similar manner, fungicidal compositions containing 50, 100, 300, 500, and 700 parts per million of *o*-toluidine chromium tricarbonyl are prepared by thoroughly blending the requisite amount of the carbonyl with Base 21.

Similarly, fungicidal compositions containing 0.1, 0.5, 1, 3, 5, 7, 10, 15, 20, and 30 percent of *o*-toluidine chromium tricarbonyl are prepared by adding the requisite portions of the carbonyl to the required portion of Base 21.

Example XII

Fungicidal compositions containing 500 parts per million of chlorobenzene chromium tricarbonyl are prepared by adding 500-part-portions of the carbonyl to 999,500-part-portions of Bases 22-35.

Similar compositions containing 500 parts per million

of arene chromium tricarbonyl are prepared by adding 500 part-portions of aniline chromium tricarbonyl, dimethylaniline chromium tricarbonyl, anisole chromium tricarbonyl, mesitylene chromium tricarbonyl, methylbenzoate chromium tricarbonyl, benzene chromium tricarbonyl, acetophenone chromium tricarbonyl, and benzophenone chromium tricarbonyl, to 999,500-part portions of Bases 22-35.

Similar fungicidal compositions are prepared by adding 300-part portions of toluene chromium tricarbonyl to 999,700-part portions of Bases 22-35. These compositions contain 300 parts per million of the fungicidal arene chromium tricarbonyl. Similarly, methylbenzoate chromium tricarbonyl, 50-part portions, is added to 999,950-part portions of Bases 22-35 to prepare fungicidal compositions which contain 50 parts per million of methylbenzoate chromium tricarbonyl.

Another preferred type of fungicidal composition comprising an emulsion contains a fungitoxic amount of an arene Group VIB metal tricarbonyl in an emulsion which contains an oleaginous substance, an ester, and water. The emulsion bases of this embodiment are similar to those above except they do not contain a long-chain alcohol. In general, bases of this type contain, per each 100 parts of oleaginous substance, from about 10 to about 1500 parts of an ester derived from a carboxylic acid having from about 12 to about 20 carbon atoms, and an alcohol having from about 3 to about 6 carbon atoms. Preferably, from about 11 to about 400 parts of ester are employed, and most preferably, from about 11 to about 35 parts of ester.

As with the esters employed in the alcohol-oil-water emulsions described and illustrated above, there is no exact limitation on the number of carbon atoms in the alcohol or acid portion of the ester. All that is required is that the ester yield a suitable emulsion when combined with the oleaginous substance and water. Highly preferred esters are illustrated by diethyleneglycol monostearate, diglycol stearate, glyceryl monostearate, isopropylmyristate, sorbitane monooleate, polyethyleneglycol 1000 monostearate, and the like. Polyethyleneglycol 1000 is an alcohol having the molecular weight of 1000, derived by polymerizing ethyleneglycol. The specific esters mentioned immediately above can be employed in the preparation of bases such as those illustrated by Bases 17-35, and similarly, the esters incorporated in those bases can be employed in the preparation of oleaginous substance-ester-water emulsions of the type illustrated below.

The ester-water-oil emulsions illustrated below, like the anhydrous and alcohol-water-oil preparations described and illustrated above, preferably contain an opaque inert insoluble substance and/or a hindered phenol of the types described and illustrated above. In general, the amounts of the phenol and opaque substance are identical to the amounts employed in the above compositions. However, higher and lower quantities can be employed if desired.

Thus, a preferred embodiment of this invention comprises a fungicidal composition containing

(1) As a principal active ingredient, at least one arene Group VIB metal tricarbonyl having the formula

wherein M is a metal of Group VIB of the Periodic Table; X is a halogen; α is an integer having the value 0 to 1; Y is selected from the class comprising

11

wherein R_1 and R_2 are alike or different and selected from the class consisting of hydrogen and alkyl groups having one to about 4 carbon atoms; b is an integer having the value 0 to 1; R is selected from the class consisting of hydrogen and alkyl groups having one to about 4 carbon atoms, and c is an integer having the value 0 to 3, such that when $c=3$, $a=0$ and $b=0$, and

(2) As a carrier therefor, an emulsion base comprising an oleaginous substance and, for each 100 parts per weight of said oleaginous substance, from about 10 to about 1500 parts of an ester derived from a carboxylic acid having from about 13 to about 20 carbon atoms and an alcohol having from about 3 to about 6 carbon atoms; and from about 11 to about 7500 parts of water.

Highly preferred compositions of this embodiment are further characterized in that they contain from about 10 to about 50 parts of an insoluble inert opaque solid.

Other highly preferred compositions of this embodiment are further characterized in that they contain from about 0.001 to about 5% of a hindered phenol having Formula II.

Bases employed in this embodiment are illustrated by the bases of Table 3. In the table, the figures in the columns are parts by weight.

Example XIII

Methylbenzoate chromium tricarbonyl, 30 parts, is thoroughly mixed with 999,970 parts of Base 38. The resultant fungicidal composition has a concentration of arene chromium tricarbonyl equal to 30 parts per million.

In a similar manner, using the same base, fungicidal compositions containing 50, 100, 300, 500, and 700 parts per million of methylbenzoate chromium tricarbonyl are prepared.

More concentrated foams containing 0.1, 0.5, 1, 3, 5, 7, 10, 15, 20 and 30 percent of arene chromium tricarbonyl are prepared by adding the requisite quantity of methylbenzoate chromium tricarbonyl to Base 38.

Example XIV

o-Xylene chromium tricarbonyl, 30 parts, is added to 999,970 parts of Base 38 to yield a fungicidal composition having 30 parts per million of arene chromium tricarbonyl.

In a similar manner, using the same base, fungicidal compositions containing 50, 100, 300, 500 and 700 parts per million of *o*-xylene chromium tricarbonyl are prepared. More concentrated foams containing 0.1, 0.5, 1, 3, 5, 7, 10, 15, 20, and 30 percent of arene chromium tricarbonyl are prepared by adding the requisite quantity of *o*-xylene chromium tricarbonyl to Base 38.

12

Example XV

p-Xylene chromium tricarbonyl, 30 parts, is added to 999,970 parts of Base 37 to yield a fungicidal composition having 30 parts per million of arene chromium tricarbonyl.

In a similar manner, using the same base, fungicidal compositions containing 50, 100, 300, 500, and 700 parts per million of *p*-xylene chromium tricarbonyl are prepared. More concentrated foams containing 0.1, 0.5, 1, 3, 5, 7, 10, 15, 20, and 30 percent of arene chromium tricarbonyl are prepared by adding the requisite quantity of *p*-xylene chromium tricarbonyl to Base 37.

Example XVI

o-Toluidine chromium tricarbonyl, 30 parts, is added to 999,970 parts of Base 36 to yield a fungicidal composition having 30 parts per million of arene chromium tricarbonyl.

In a similar manner, using the same base, fungicidal compositions containing 50, 100, 300, 500 and 700 parts per million of *o*-toluidine chromium tricarbonyl are prepared. More concentrated foams containing 0.1, 0.5, 1, 3, 5, 7, 10, 15, 20, and 30 percent of arene chromium tricarbonyl are prepared by adding the requisite quantity of *o*-toluidine chromium tricarbonyl to Base 36.

Example XVII

Fungicidal compositions are prepared by adding 100-part-portions of methylbenzoate chromium tricarbonyl to 9900-part-portions of Bases 36, 37, 39 and 40. The compositions contain 1% of methylbenzoate chromium tricarbonyl. Similar fungicidal compositions containing 0.5% of an arene chromium tricarbonyl are prepared by adding 50-part portions of aniline chromium tricarbonyl, toluene chromium tricarbonyl, chlorobenzene chromium tricarbonyl, benzene chromium tricarbonyl, and mesitylene chromium tricarbonyl, to 9950-part portions of Bases 36-40.

Similar compositions are prepared by adding 20-part portions of bentonite to 80-part portions of Bases 36-40 and thoroughly mixing. Thereafter, 99.5-part portions of the bentonite-containing bases are then thoroughly blended with 0.5-part portions of methylbenzoate chromium tricarbonyl, *o*-xylene chromium tricarbonyl, *p*-xylene chromium tricarbonyl, and *o*-toluidine chromium tricarbonyl.

Example XVIII

4,4'-methylenebis(2,6-di-*tert*-butylphenol), 0.25 part, 20 parts of fuller's earth, and 79.75 parts of Base 38 are thoroughly blended. The resultant base is then divided into five 9.5-part portions. To the first 9.5-part portion is added 0.5 part of methylbenzoate chromium tricarbonyl. To each of the other 9.5-part portions is added 0.5 part of *o*-toluidine, *p*-xylene, *o*-xylene, and aniline chromium tricarbonyl respectively. The resultant fungicidal compositions contain 5% of the respective fungitoxic arene Group VIB metal tricarbonyl.

Other bases which do not have an oleaginous substance can be employed to prepare preferred fungicidal compositions of this invention. Thus, another preferred embodiment of this invention comprises:

(1) As a principal active ingredient, a fungitoxic amount of at least one arene Group VIB metal tricarbonyl having the formula

75 wherein M is a metal of Group VIB of the Periodic Table,

X is a halogen; a is an integer having the value 0 to 1; Y is selected from the class comprising

wherein R₁ and R₂ are alike or different and selected from the class consisting of hydrogen and alkyl groups having one to about 4 carbon atoms; b is an integer having the value 0 to 1; R is selected from the class consisting of hydrogen and alkyl groups having one to about 4 carbon atoms, and c is an integer having the value 0 to 3, such that when c=3, a=0 and b=0, and

(2) As a carrier therefor, an ester-water emulsion comprising an ester derived from an acid having from about 13 to about 20 carbon atoms and an alcohol having from about 3 to about 6 carbon atoms and, per each 100 parts of ester, from about 20 to about 100 parts of an insoluble, inert, opaque solid, and from about 300 to about 780 parts of water.

Highly preferred compositions of this type are further characterized in that they contain from about 0.001 to about 5% of a hindered phenol. The esters and insoluble inert opaque solids described above can be employed in this embodiment. Bases employed in this embodiment are illustrated by those in Table 4 wherein the figures in the columns are parts by weight.

Example XIX

Methylbenzoate chromium tricarbonyl, 30 parts, is thoroughly mixed with 999,970 parts of Base 41. The resultant fungicidal composition has a concentration of arene chromium tricarbonyl equal to 30 parts per million.

In a similar manner, using the same base, fungicidal compositions containing 50, 100, 300, 500, and 700 parts per million of methylbenzoate chromium tricarbonyl are prepared.

More concentrated foams containing 0.1, 0.5, 1, 3, 5, 7, 10, 15, 20 and 30 percent of arene chromium tricarbonyl are prepared by adding the requisite quantity of methylbenzoate chromium tricarbonyl to Base 41.

Example XX

o-Toluidine chromium tricarbonyl, 30 parts, is thoroughly mixed with 999,970 parts of Base 43. The resultant fungicidal composition has a concentration of arene chromium tricarbonyl equal to 30 parts per million.

In a similar manner, using the same base, fungicidal compositions containing 50, 100, 300, 500, and 700 parts per million of *o*-toluidine chromium tricarbonyl are prepared.

More concentrated foams containing 0.1, 0.5, 1, 3, 5, 7, 10, 15, 20, and 30 percent of arene chromium tricarbonyl

are prepared by adding the requisite quantity of *o*-toluidine chromium tricarbonyl to Base 43.

Example XXI

5 o-Xylene chromium tricarbonyl, 30 parts, is thoroughly mixed with 999,970 parts of Base 44. The resultant fungicidal composition has a concentration of arene chromium tricarbonyl equal to 30 parts per million.

In a similar manner, using the same base, fungicidal compositions containing 50, 100, 300, 500, and 700 parts per million of o-xylene chromium tricarbonyl are prepared.

More concentrated foams containing 0.1, 0.5, 1, 3, 5, 7, 10, 15, 20, and 30 percent of arene chromium tricarbonyl are prepared by adding the requisite quantity of o-xylene chromium tricarbonyl to Base 44.

Example XXII

20 p-Xylene chromium tricarbonyl, 30 parts, is thoroughly mixed with 999,970 parts of Base 44. The resultant fungicidal composition has a concentration of arene chromium tricarbonyl equal to 30 parts per million.

In a similar manner, using the same base, fungicidal compositions containing 50, 100, 300, 500, and 700 parts per million of p-xylene chromium tricarbonyl are prepared.

More concentrated foams containing 0.1, 0.5, 1, 3, 5, 7, 10, 15, 20, and 30 percent of arene chromium tricarbonyl are prepared by adding the requisite quantity of p-xylene chromium tricarbonyl to Base 44.

Example XXIII

35 Base 42 is prepared with 700 parts of water. To a 980-part portion of the resultant base is added 20 parts of 4,4'-methylenebis(2,6-di-*tert*-butylphenol). The resultant stabilized base is then divided into eight 97-part portions. To each portion is added 3 parts of methylbenzoate chromium tricarbonyl, *o*-toluidine chromium tricarbonyl, o-xylene chromium tricarbonyl, p-xylene chromium tricarbonyl, aniline chromium tricarbonyl, benzene chromium tricarbonyl, chlorobenzene chromium tricarbonyl, and toluene chromium tricarbonyl respectively. The resultant fungicidal composition contains 3% by weight of an arene chromium tricarbonyl.

To a further 97-part portion of the stabilized base is added 1.5 parts of *o*-toluidine chromium tricarbonyl and 1.5 parts of methylbenzoate chromium tricarbonyl. The resultant fungicidal composition contains 3% by weight of a mixture of arene Group VIB metal tricarbonyls.

As reported in my copending application Serial No. 161,367, the arene Group VIB metal tricarbonyls are especially efficacious in treating fungi which are pathogenic to animals and man. This has been demonstrated by the following serial dilution tests.

SERIAL DILUTION TESTS

60 Arene chromium tricarbonyls were evaluated for fungicidal activity by the serial dilution test of Burlingame and Reddish, J. Lab. Clin. Med., 24, page 765, 1939. The test fungi used in this case were *Trichophyton interdigitale*, *Trichophyton rubrum*, *Trichophyton schoenleinii*, *Microsporum audouini*, *Epidermophyton floccosum*, *Microsporum gypseum*. These fungi were grown in Difco's Sabouraud's liquid medium, pH 4.7. Sample preparation consisted of dissolving aliquots of each compound in 10 mls. of ethanol and diluting to 512 p.p.m. concentrations

70 with distilled water. These stock solutions were serially diluted through 10 tubes of culture medium. The inoculum consisted of 1 dropper tube of a heavy spore suspension of the test fungi. The tests were incubated at 35° C. for one week. Some results of these tests are as follows.

SERIAL DILUTION

[Fungi pathogenic to man and animals. Minimum effective concentration in parts/million]

*Ma = *Microsporum audouini*.Mg = *Microsporum gypseum*.Tr = *Trichophyton rubrum*.Ef = *Epidermophyton floccosum*.Ts = *Trichophyton schoenleinii*.Ti = *Trichophyton interdigitale*.

In a similar manner, the compositions of this invention are active against fungi.

The fungicidal compositions provided herein are preferably excluded from excessive light and exposure to air. Preferably they are stored in opaque, closed containers.

The fungicidal compositions of this invention are employed by applying them to the locus of the fungi. In some instances, especially when the fungicidal infection is somewhat severe, more than one application may be required. In some cases, it is desirable to cover the infected part with a sterile dressing after applying the composition.

The compositions are especially efficacious against fungi which are pathogenic to animals and man, such as *Microsporum audouini*, *Microsporum gypseum*, *Trichophyton rubrum*, *Epidermophyton floccosum*, *Trichophyton schoenleinii*, *Trichophyton interdigitale*, and the like.

Having fully described the novel compositions of this invention, the method of employing them, and their many utilities, I desire that the scope of this invention be limited only by the lawful scope of the appended claims.

I claim:

1. A fungicidal composition comprising

(1) as a principal active ingredient, a fungitoxic amount of a compound having the formula

50

wherein X is a halogen; a is an integer having the value 0 to 1; Y is selected from the class comprising

55

wherein R₁ and R₂ are independently selected from the class consisting of hydrogen and alkyl groups having one to 4 carbon atoms; b is an integer having the value 0 to 1; R is selected from the class consisting of hydrogen and alkyl groups having one to 4 carbon atoms, and c is an integer having the value 0 to 3, such that when c=3, a=0 and b=0; and (2) as a carrier therefor, a non-toxic, non-drying, inert oleaginous substance, and, for each 100 parts by weight of said oleaginous substance, from about 5 to about 30 parts of an alcohol having from about 16 to about 30 carbon atoms.

2. A composition of claim 1 being further characterized in that said carrier comprises, per each 100 parts of said oleaginous substance, from about 10 to about 50 parts of an inert, opaque, insoluble non-toxic solid.

3. A composition of claim 2 wherein said inert solid is stearic acid.

4. The composition of claim 2 wherein said inert solid is bentonite.

5. A composition of claim 2 having from about 0.001 to about 2 percent by weight of a phenol having the formula

wherein the groups designated by R₁ and R₂ are alkyl groups containing from 3 to 8 carbon atoms and are further characterized by being branched on their alpha carbon atoms.

6. A composition of claim 5 wherein said phenol is 4,4'-methylenebis(2,6-di-tert-butylphenol).

7. A fungicidal composition comprising

(1) as a principal active ingredient, a fungitoxic amount of an arene chromium tricarbonyl having the formula

wherein X is a halogen; a is an integer having the value 0 to 1; Y is selected from the class comprising

wherein R₁ and R₂ are independently selected from the class consisting of hydrogen and alkyl groups having one to 4 carbon atoms; b is an integer having the value 0 to 1; R is selected from the class consisting of hydrogen and alkyl groups having one to 4 carbon atoms, and c is an integer having the value 0 to 3, such that when c=3, a=0 and b=0; and

(2) as a carrier therefor, an emulsion comprising a non-toxic, non-drying, inert oleaginous substance and, for each 100 parts of said oleaginous substance,

from about one to about 31 parts of a monohydric alcohol having from about 13 to about 30 carbon atoms,

from about 2 to about 6 parts of an alkali metal-containing anionic surfactant, and

from about 95 to about 310 parts of water.

8. A composition of claim 7 being further characterized in that said carrier contains, for each 100 parts of

75 said oleaginous substance,

17

from about 8 to about 12 parts of an ester derived from an acid having from about 12 to about 20 carbon atoms and an alcohol having from about 3 to about 6 carbon atoms.

9. A composition of claim 8 being further characterized in that said carrier also contains from about 10 to about 50 parts of an inert, insoluble, opaque, non-toxic solid.

10. A composition of claim 9 being further characterized in that it contains from about 0.001 to about 2 percent of a phenol having the formula

15

wherein the groups designated by R₁ and R₂ are alkyl groups containing from 3 to 8 carbon atoms and are further characterized by being branched on their alpha carbon atoms.

11. A fungitoxic composition comprising

(1) as a principal active ingredient a fungicidal amount of an arene chromium tricarbonyl having the formula:

30

wherein X is a halogen; a is an integer having the value 0 to 1; Y is selected from the class comprising

40

wherein R₁ and R₂ are independently selected from the class consisting of hydrogen and alkyl groups having one to 4 carbon atoms; b is an integer having the value 0 to 1; R is selected from the class consisting of hydrogen and alkyl groups having one to 4 carbon atoms, and c is an integer having the value 0 to 3, such that when c=3, a=0 and b=0; and

(2) as a carrier therefor, a substantially long chain-alcohol-free emulsion comprising a non-toxic, non-drying inert, oleaginous substance, and per each 100 parts of said oleaginous substance,

from about 10 to about 1500 parts of an ester derived from a long-chain carboxylic acid having from about 13 to about 20 carbon atoms and an alcohol having from about 3 to about 23 carbon atoms, and

from about 80 to about 7500 parts of water.

12. A composition of claim 11 being further characterized in that said carrier comprises, per each 100 parts of said oleaginous substance, from about 10 to about 50 parts of an insoluble inert, opaque, solid.

13. A composition of claim 12 containing from about 0.001 percent to about 2 percent of a phenol having the formula

18

wherein the groups designated by R₁ and R₂ are alkyl groups containing from 3 to 8 carbon atoms and are further characterized by being branched on their alpha carbon atoms.

14. A fungicidal composition comprising

(1) as a principal active ingredient, a fungitoxic amount of an arene chromium tricarbonyl having the formula

wherein X is a halogen; a is an integer having the value 0 to 1; Y is selected from the class comprising

wherein R₁ and R₂ are independently selected from the class consisting of hydrogen and alkyl groups having one to 4 carbon atoms; b is an integer having the value 0 to 1; R is selected from the class consisting of hydrogen and alkyl groups having one to 4 carbon atoms, and c is an integer having the value 0 to 3, such that when c=3, a=0 and b=0; and (2) as a carrier therefor, an emulsion comprising an ester derived from a carboxylic acid having from about 13 to about 20 carbon atoms, and an alcohol having from about 3 to about 6 carbon atoms and, per each 100 parts of said ester,

from about 20 to about 100 parts of an inert opaque insoluble solid and from about 330 to about 770 parts of water.

15. A composition of claim 14 comprising from about 0.001 to about 2 percent of a phenol having the formula

wherein the groups designated by R₁ and R₂ are alkyl groups containing from 3 to 8 carbon atoms and are further characterized by being branched on their alpha carbon atoms.

16. A method for treating fungi comprising treating the locus of the fungi with the composition of claim 1.

17. A method of combating fungi comprising treating the locus of the fungi with the composition of claim 7.

18. A method of combating fungi comprising treating the locus of the fungi with the composition of claim 11.

19. A method of combating fungi comprising treating the locus of the fungi with the composition of claim 14.
